AUTOMATIC STARTING MECHANISM

Maurice P. Whitney, Elmira, N. Y., assignor to Eclipse Machine Company, Elmira, N. Y., a corporation of New York

Application February 24, 1931, Serial No. 518,012

4 Claims. (Cl. 290—38)

This invention relates to automatic starting mechanism for internal combustion engines and more particularly to such a mechanism including a device for cutting off the power from the 5 starter in case said starter is subjected to sustained overload. Such a condition is sometimes brought about by an attempt to start a motor vehicle with the transmission gears engaged and the brakes set, or by abutting or jamming of the 10 ends of the teeth of a starting pinion against the teeth of an engine gear. When an electrical starting motor is thus prevented from rotating, the battery is subjected to a heavy current drain, and the energy thereof is dissipated as heat within 15 in the starting motor and other elements of the starting circuit.

It is an object of the present invention to provide an automatic electrical starting mechanism embodying a novel device for opening the 20 motor circuit in response to an overload, which device is simple and economical to construct and reliable in operation.

Another object of the invention is to provide such a device which operates automatically to 25 open the starting circuit and hold said circuit open until reset by the operator.

A further object is to provide such a device in which the resetting is accomplished by the 30 operation of a manual switch such as the ignition switch of the engine, which is also arranged to control the operation of the automatic starting mechanism.

Further objects and advantages will be apparent to those skilled in this art from the following description taken in connection with the accompanying drawing in which the single figure is a semi-diagrammatic illustration of the preferred form of the invention, the automatic starting switch being shown in elevation and 40 partly in section.

In the drawing there is illustrated a starting circuit including a battery 10 having one terminal grounded at 11 and the opposite terminal connected by a lead 12 to an automatic starting 45 switch comprising stationary elements 13 and 14 and a movable bridging element 16. Switch element 14 is connected through a single turn coil 17 and lead 18 to a conductor 19 which in turn is connected by a lead 20 to a starting motor SM 50 which is grounded at 21. The single turn coil 17 is provided with an adjustable magnetic core 22 which is surrounded by a spacing sleeve 23.

The movable starting switch element 16 is mounted on a magnetic switch plunger 24, suitably insulated therefrom, which plunger is nor-

mally retained in its upper position as illustrated by suitable means such as a spring 26. A solenoid 27 is arranged to surround the lower end of switch plunger 24 and is adapted when energized to draw the plunger down in order to close 60 the starting switch.

Solenoid 27 forms one element of a control circuit for the starting switch which includes a manual switch 28, which is preferably the ignition switch of the engine and which is connected to the battery lead 12, a lead 29, a heat-responsive element 30, normally closed contacts 31 and 32, lead 33, lead 34, normally closed contacts 36 and 37, spring strip 38 and ground connection 39.

Contact 36 is stationary while contact 37 mounted on spring strip 38 is adapted to be moved out of engagement therewith by means of a lever 40 pivoted at one end at 41 and having a roller 42 on its free end adapted to engage a weight member 43 on the end of the spring strip 38 and bend said strip backward. Lever 40 is provided intermediate its length with a pin 44 adapted to extend laterally between a pair of flanges 46 and 47 on a magnetic relay plunger 48. The relay 75 plunger is normally held in its upper position in contact with the spacing sleeve 23 by suitable means such as a spring 49, so that the roller 42 is out of engagement with the member 43 and contact 37 is therefore allowed to engage the fixed 80 contact 36. The lower end of relay plunger 48 is surrounded by a voltage coil 50 and a generator coil 51 which when energized attract the relay plunger downward. Voltage coil 50 is connected to the starting switch element 14 by a lead 52, 90 and is grounded at its opposite terminal at 53. The generator coil 51 is connected at one end to the generator G by a lead 54, the opposite end of said coil being grounded at 53.

The heat-responsive element 30 is in the form 95 of a bi-metallic strip fixedly mounted at one end as by means of a bracket 56 and carrying the movable contact 31 on its free end. The bi-metallic element 30 is so positioned that the contact 31 on the free end thereof is normally in engagement with the fixed contact 32 but an increase in temperature of said element will cause the free end thereof to bend upwardly and move the contact 31 out of such engagement.

Suitable heating means for the heat-responsive 105 element 30 is provided such as a ribbon of resistance metal 57, wrapped around the heat-responsive element 30 and connected in shunt with the conductor 19 as illustrated. It will be seen from this arrangement that the heating element 57 will 110

be traversed by an aliquot portion of the total current traversing the starting circuit and the heating effect thereof on the element 30 will therefore be proportional to the load on the starting circuit. Since a predetermined rise in temperature of the element 30 will cause the contact 31 to move out of engagement with contact 32, it is evident that this arrangement provides means for opening the control circuit and consequently 10 breaking the starting circuit in response to a predetermined overload on the starting motor.

According to the present invention, means are provided for preventing the return of the heat-responsive element 30 to its normal position after 15 it has been actuated to open the contacts 31, 32, until the operator has reset the device for further automatic operation. As here illustrated, this means takes the form of a latch member 58 in the form of a bell crank lever pivoted at 59 and having an arm 60 provided with a notch 61 adapted to receive the end of the heat responsive element 30 when the arm 60 is pressed toward said element. In order to move the arm 60 into such engaging position, an arm 62 of the bell 20 crank lever is provided with a magnetic plunger 63 which is adapted to be actuated by a solenoid 64. Solenoid 64 is connected at one end by a lead 66 to the lead 29 from the manual switch 28, and is grounded at its other end at 67. Means such as a spring 68 is provided for yieldably urging the 25 arm 60 in a direction to release the end of the heat-responsive member 30 when the solenoid 64 is deenergized.

In operation, and starting with the parts in the 30 position illustrated in the drawing, closure of the manual switch 28 completes a circuit from battery 10 through lead 12, switch 28, lead 29, bracket 56, heat-responsive element 30, contacts 31, 32, lead 33, switch coil 27, lead 34, contacts 36, 37, 35 spring strip 38 and ground connection 39. The consequent energization of switch coil 27 draws the switch plunger 24 downward causing the starting switch member 16 to close the starting circuit whereupon the starting motor is energized to crank the engine. At this time the voltage coil 52 is energized by reason of its connection to the starting switch member 14 but does not draw the relay plunger 48 downward since the heavy starting current traversing the single turn coil 17 magnetizes the core 22 thereof sufficiently to 40 retain the relay plunger in its upper position.

When the engine becomes self-operative, the 45 relief of the load on the starting motor causes a large reduction in the current traversing the starting circuit, thus weakening the effect of the single turn coil 17 and strengthening the voltage coil 50 by reason of the increased voltage drop therethrough so that said plunger is drawn downward causing the roller 42 to engage the weight member 43 and bend the spring strip 38 backward, moving contact 37 out of engagement with contact 36. The control circuit is thus broken, de-energizing the switch coil 27 and allowing the spring 26 to open the starting switch. The voltage coil 50 however, retains the plunger 48 in its lower position due to a slight amount of current generated by the starting motor spinning in its residual field. Before the starting motor slows down sufficiently to deenergize the voltage coil, the generator G which is driven from the engine picks up sufficiently to energize the generator coil 51 and thus retain the plunger 48 in its lower position.

If, during the starting operation, the engine 75 should be prevented from rotation as by being

left in gear, or if the starting pinion should engage end to end with the engine gear, and become wedged therewith, a heavy current will be caused to traverse the starting circuit since the starting motor is unable to rotate and generate any counter electro-motive force. A proportional part of this heavy flow of current traverses the heating element 57, which accordingly raises the temperature of the bi-metallic element 30, causing the same to bend upward and engage in the notch 61 of the lever arm 60 with the contact member 31 out of engagement with contact 32. The control circuit is thus broken and the starting switch allowed to open.

Closure of the manual switch 28 completes an electrical circuit from battery 10 through lead 12, switch 28, lead 29, lead 66 and solenoid 64 to the ground at 67. The consequent energization of solenoid 64 causes the arm 60 of latch 58 to be urged toward the heat-responsive element 30. When, therefore, said member bends upwardly, the end thereof enters the notch 61 in the arm 60, and is retained thereby as long as the manual switch 28 remains closed. The starting mechanism is thus held in inoperative position until the operator has taken the necessary steps to free the starting gearing and allow operation thereof.

In order to reset the device for further automatic operation, it is only necessary for the operator to open the manual switch 28 whereupon the solenoid 64 is deenergized and the spring 68 retracts the arm 60, allowing the heat-responsive element 30 to escape from the notch 61 and close the contacts 31, 32. Subsequent closure of the manual switch 28 causes the automatic starting operation to be repeated.

Although but one form of the invention has been illustrated and described in detail, it will be understood that various other embodiments are possible and that various changes may be made in the proportions and arrangements of the parts without departing from the spirit of the invention as defined in the claims appended hereto.

What is claimed is:

1. Automatic starting mechanism for internal combustion engines including a starting motor circuit having an automatic starting switch, a control circuit for said starting switch having a manual switch therein, means responsive to an overload on the starting circuit for breaking said control circuit, and means controlled by said manual switch for maintaining said break in the control circuit.

2. In an automatic starting mechanism for internal combustion engines, a starting circuit including an automatic starting switch, a control circuit for said starting switch including a pair of contacts, a member adapted when heated to operate said contacts to cause the starting switch to be opened, means for heating said member arranged to be energized by current traversing the starting circuit, means for preventing the return of the heat-responsive member to normal position and manual means for releasing said preventing means.

3. In an automatic starting mechanism for internal combustion engines, a starting circuit including an automatic starting switch, a control circuit for said starting switch including a manual switch and a pair of contacts, a member adapted when heated to operate said contacts to cause the starting switch to be opened, means for heating said member arranged to be energized by current traversing the starting circuit and means
